UNITED STATES PATENT OFFICE.

KARL G. KUTCHKA, OF WILKINSBURG, PENNSYLVANIA, ASSIGNOR TO PITTSBURGH PLATE GLASS COMPANY, A CORPORATION OF PENNSYLVANIA.

APPARATUS FOR ROLLING GLASS.

Application filed June 9, 1926. Serial No. 114,732.

The invention relates to apparatus for rolling glass, and particularly to the means for cooling the rolls between which the glass sheet is formed. These rolls are ordinarily made of cast iron, and are cooled by passing a flow of water therethrough. Due to the thickness of the walls of the rolls, the cooling afforded by the water is sometimes insufficient to cool the rolls as much as is necessary when the speed of the formation of the sheet is increased beyond a certain point. The capacity of the apparatus is, therefore, limited by the cooling capacity of the rolls, which is an undesirable condition, particularly as a better product is produced when the speed of formation of the sheet is relatively high. The lack of sufficient cooling capacity in the rolls also tends to produce warping thereof, so that the glass sheet varies in thickness. The object of the present invention is to provide a simple, effective means for increasing the cooling capacity of the rolls, and particularly that of the lower roll, which is heated to a greater extent than the upper one, due to the fact that the area of contact with this roll is greater, since the sheet follows around its periphery a considerable distance before it reaches the runway for supporting the sheet after it leaves the rolls. Briefly stated, this is accomplished by the provision of surface cooling means, applied in such manner, that a large volume of air is passed over the peripheries of the rolls, which are very highly heated and thus subject to very effective cooling by the air, because of the large difference in temperature of the iron and the cooling medium. The arrangement is preferably such that the cooling effect of the air is confined to the roll surfaces, thus avoiding any disturbance of temperature conditions of other parts in the vicinity of the rolls. Certain embodiments of the invention are shown in the accompanying drawings, wherein:

Figure 1 is a partial vertical section through the apparatus. Fig. 2 is a partial horizontal section and partial plan view of a pair of header castings. Fig. 3 is a plan view of the pipes looking downward from the line III-III of Fig. 1. Fig. 4 is a section on the line IV-IV of Fig. 3. And Figs. 5 and 6 are partial vertical sections through modified forms of construction.

Referring to the drawings, 1 and 2 are a pair of forming rolls between which the glass sheet is rolled continuously, such rolls being hollow and being cooled by a flow of liquid through the center openings 4, 4. The glass is supplied between the lip members 5, 5 from a body of molten glass 6 carried by a tank, which is not shown. The method of supplying glass to the rolls is immaterial in so far as the present invention is concerned, such invention, as heretofore indicated, relating to the means employed for cooling the rolls upon their exterior surfaces. The glass sheet 3 passes over a runway comprising the rolls 7, after which it is conducted into and through a leer. The upper roll is cooled upon its exterior by means of a flow of air from the header 8 which extends longitudinally of the roll and is provided with the outlet passages 9, air being supplied to the header under pressure from suitable blower apparatus, not shown.

Extending longitudinally beneath the lower roll 2 is a series of header castings 10, 11, etc., of similar construction, the header 11 being shown in plan view (Fig. 2), while the header 10 is shown on a section taken on the line II-II of Fig. 1. Each of these headers comprises a discharge chamber 12 and a suction chamber 13, the discharge chamber being provided with a plurality of outlets 14 for delivering air or other cooling fluid under pressure against the periphery of the roll and circumferentially thereof. The air as thus supplied and carried around the periphery of the roll, is withdrawn through the suction chamber 13. In order to prevent any leakage between the roll and the left hand wall of the suction chamber, a flexible packing member 15 is provided carried by the wall of the suction chamber and bearing against the surface of the roll. This packing member may be made of asbestos or any other suitable material. The outlets 14 are directed at an angle, as illustrated, so that there will be no escape of air at the point 16, the flow of air to the left from the outlets causing a suction at this point rather than a pressure. A flow of air outward at this point is regarded as undesirable, as it would tend to unduly chill the sheet 3 passing over the runway. Each suction chamber is provided with an angular connection 17 connected to a vertical pipe 18, and this vertical pipe 18 is in turn con-

nected to a horizontal suction pipe 19, as indicated in Fig. 4. In the construction illustrated, there are four suction chambers 13, each connected to a vertical pipe 18 leading to the pipe 19 (Fig. 3), the arrangement for exhausting the air from all of the chambers being the same as that just above described. Similarly, each of the discharge chambers 12 is provided with a laterally and downwardly extending passage 20 corresponding to the passage 17 and connected to the upper ends of the vertical pipes 21 lying alongside the vertical pipes 18 (Fig. 3). These pipes 21 extend downwardly and laterally into a supply pipe 22 lying beneath the suction pipe 19 and parallel thereto. A suitable suction fan is provided for exhausting air from the pipe 19 and a blower is connected to the pipe 22 for supplying the necessary air therethrough under pressure.

In operation, a large volume of air is supplied to the discharge chambers 12 and passes through the outlet passages 14. The air thus supplied flows circumferentially of the roll to the suction chambers 13, at which time it is received and carried away by the suction from the pipe 19. In this manner, a maximum amount of cooling fluid is carried over the surface of the roll, thus giving a substantial chilling effect, and there is no escape of air which might tend to injuriously affect parts of the apparatus in the vicinity of the roll. The discharge from the upper headers 8, is also directed circumferentially of the upper roll 1, but the air as thus supplied around the roll to the right is permitted to discharge to the air, since this point is so far removed from the sheet 3 that its effect upon such sheet is not harmful.

The arrangement shown in Fig. 5 is similar to that of Fig. 1 except that in this construction the headers 23 beneath the roll 2 are arranged farther to the right so as to give more space at 24 for access to the roll and lip 5, and a baffle 25 is provided for giving a better distribution of air through the header, as indicated by the arrow. The air is withdrawn through the suction chamber 27 as in the other type of construction. The upper header 26 is also similar to the upper header in the Fig. 1 construction with the exception that a baffle 28 is employed similar to the baffle 25.

Fig. 6 illustrates a modification of the lower header, in which two suction chambers 29 and 30 are employed on opposite sides of the discharge chamber 31, and in this construction the outlets 32 are arranged vertically instead of at an angle. A pair of asbestos packing plates 33 and 34 are employed bearing against the roll, as shown, in order to prevent leakage at these points. In this construction, the flow of air is circumferential of the roll in both directions

instead of being in the one direction only as in the Fig. 1 construction. A suitable blower is connected to the discharge chamber, while the suction chambers are provided with connections leading to a suitable exhaust apparatus.

What I claim is:

1. The combination in glass rolling apparatus having a pair of internally water cooled rolls, of supplemental cooling means for one of the rolls, comprising a header extending longitudinally thereof along one side and provided with outlet means along one side directed against the surface of the roll and means for supplying a gaseous cooling fluid to said header under pressure.

2. The combination in glass rolling apparatus, having a pair of rolls through which glass is supplied, of cooling means for one of the rolls, comprising a header extending along one of the rolls and having its side hollowed out so as to fit around the periphery of the roll, with outlet means leading through such side, means for supplying gaseous cooling fluid to the header under pressure, a second header at one side of the first header fitting around the roll and having an inlet opening toward the rolls and means for applying suction to such second header.

3. The combination in glass rolling apparatus, having a pair of rolls through which glass is supplied, of cooling means for one of the rolls, comprising a header extending along one of the rolls and having its side hollowed out so as to fit around the periphery of the roll, with outlet means leading through such side, and inclined obliquely with respect to the roll, and means for supplying gaseous cooling fluid to the header under pressure to cause a flow thereof through said outlet means and around the roll in one direction.

4. The combination in glass rolling apparatus, having a pair of rolls through which glass is supplied, of cooling means for one of the rolls, comprising a header extending along one of the rolls and having its side hollowed out so as to fit around the periphery of the roll with outlet means leading through such side, and inclined obliquely with respect to the roll, means for supplying gaseous cooling fluid to the header under pressure to cause a flow thereof through said outlet means and around the roll in one direction, a second header on the side of the first header toward which the gaseous fluid from the outlet means is directed fitting around the roll and having an inlet opening toward the roll, and means for applying suction to such second header.

5. The combination in glass rolling apparatus, having a pair of rolls through which glass is supplied, of cooling means for one of the rolls, comprising a header extending

- along one of the rolls and having its side hollowed out so as to fit around the periphery of the roll, with outlet means leading through such side, means for supplying gaseous cooling fluid to the header under pressure, a second header at one side of the first header fitting around the roll and having an inlet opening toward the rolls, and means for applying suction to such second header, flexible packing means being provided between the roll and the outer side of the second header. 6. The combination in glass rolling apparatus, having a pair of rolls through which glass is supplied, of cooling means for one of the rolls, comprising means for supplying a gaseous cooling fluid against the surface of the roll and causing it to flow circumfer- entially thereof, and suction means for withdrawing the fluid after it has passed partially around the roll. 7. In glass rolling apparatus, a roll, means for circulating a cooling fluid through the roll, a supplemental cooling means, comprising a header extending longitudinally of the roll and having its side hollowed out so as to fit around the periphery of the roll and provided with outlet means along one side directed against the surface of the roll, and means for supplying a gaseous cooling fluid to said header under pressure.
- 15 In testimony whereof, I have hereunto subscribed my name this 11th day of May, 1926.

KARL G. KUTCHKA.
